BOWLING BALL OR THE LIKE

Fred E. Satchell, Grand Haven, Mich., assignor to Brunswick Corporation, Chicago, Ill., a corporation of Delaware

Filed Mar. 14, 1963, Ser. No. 73,971

Term of patent 14 years

(Cl. D34—15)

FIGURE 1 is a front elevational view of a bowling ball or the like showing my new design;

FIGURE 2 is a rear view thereof upon pivoting 180° from FIGURE 1 about a vertical axis;

FIGURE 3 is a top view thereof upon pivoting the top of the ball forward 90° from FIGURE 1 on a horizontal axis;

FIGURE 4 is a bottom view thereof upon pivoting the bottom of the ball forward 90° from FIGURE 2 on a horizontal axis; and

FIGURE 5 is a perspective view showing the general appearance of the ball of FIGURES 1-4.

The dominant features of my design reside in the combination on the bowling ball surface disclosed of the free

form shaded portions contrasting generally with the remainder of the surface. These features are shown in full lines on the drawing.

I claim:

The ornamental design for a bowling ball or the like, as shown and described.
